all,

UNITED STATES PATENT OFFICE.

CHARLES CORNWELL HOVEY, OF BAINBRIDGE, NEW YORK.

APPARATUS FOR SEALING CANS, JARS, AND OTHER PACKAGES BY ATMOSPHERIC PRESSURE.

No. 826,249.

Specification of Letters Patent.

Patented July 17, 1906.

Application filed July 15, 1905. Serial No. 269,820.

To all whom it may concern:

Be it known that I, CHARLES CORNWELL HOVEY, a citizen of the United States, residing at Bainbridge, in the county of Chenango 5 and State of New York, have invented an Improvement in Apparatus for Sealing Cans, Jars, and other Packages by Atmospheric Pressure, of which the following is a specification.

10 My invention relates to a unitary apparatus or series of coating devices for effecting the sealing by atmospheric pressure of cans, jars, and other packages containing foods.

In the application for Letters Patent filed 15 by me March 6, 1905, Serial No. 248,390, I have shown and described a machine for receiving the cans, jars, &c., and in which the vacuum is established for sealing the covers and which machine is similar to the one 20 shown and described herein.

In carrying out my present invention I employ a machine including a receptacle receiving the cans, jars, &c., and in which the covers are sealed by atmospheric pressure, a vacuum-tank, an air-pump, a pipe from said machine to the air-pump and in which is located a three-way valve, a pipe from the vacuum-tank to the aforesaid pipe and joined therewith between the three-way valve and the 25 air-pump, and a two-way valve in the said pipe.

The details of the unitary apparatus and the operation of the same are hereinafter described.

30 In the drawing I have represented the unitary device of my improvement by an elevation in which the cover of the receptacle is shown as open, so as to disclose the parts therein.

35 The machine illustrated for receiving the cans, jars, &c., and in which the vacuum is established for sealing the covers and which is similar to the one shown and described in my application hereinbefore noted, com-

40 prises a standard *a*, shown as hollow, a receptacle *b*, comprising a top, bottom, sides and back, and a cover *b'*, shown in a horizontal position, but adapted to set up into a vertical position to close the receptacle. The platform

45 *c* shown within the receptacle is adapted to receive the cans, jars, &c., the covers of which are to be sealed by atmospheric pressure. This cover is connected to a rod *c'*, which

passes down through the bottom of the receptacle and through the standard and is connected to one end of a foot-lever *c'*, by which the said platform and the articles thereon are adapted to be raised. *d* represents a platen also in said receptacle and connected to a screw-rod *d'*, which passes up through a stuffing-box in the cover of the receptacle and through a brace-bar *d''*, terminating in a hand-wheel by which the screw is rotated and the platen *d* raised and lowered.

e represents a gage connected upon the top 65 of the receptacle with the inside, so as to indicate the vacuum present.

f is a vacuum tank or cylinder suitably supported, and *g* an air-pump, which latter may be of any well-known or desired construction.

h is a pipe connected to the top of the receptacle *b* and internally communicating with the receptacle and extending to the air-pump. In the line of this pipe *h* there is a three-way valve *i*, which in one position closes off the 75 pipe *h*, in another position opens up the pipe *h*, and in another position closes the communication from the receptacle *b* to the air-pump and opens a connection from the receptacle for the entrance of the atmosphere.

k is a pipe from the vacuum-tank *f* to the pipe *h*, connecting with the pipe *h* between the three-way valve *i* and the air-pump, and in this line of pipe is a two-way valve *l*, which in one position opens up communication 85 through the pipe *k* and in another position closes off the same.

In the method employed, or, in other words, in the operation of the apparatus described, the air-pump *g* is being run, the 90 valve *i* is closed in the line of pipe *h*, and the valve *l* open, so that the pump is exhausting the vacuum-tank *f*. While this is proceeding the cans, jars, or other packages the covers of which are to be sealed by atmospheric 95 pressure are placed upon the platform *c* and the platen *d* screwed down until within a short distance—say one-fourth or three-eighths of an inch—of the covers. The door *b'* of the receptacle is now closed and secured, and while the pump is still running the valve 100 *i* is opened to establish communication from the receptacle through the pipes *h* and *k* to the vacuum-tank, which, because of the vacuum therein, at once takes a large percentage 105 of the air from the receptacle and produces

in the receptacle a partial vacuum. The valve *l* is then closed and the pump allowed to work through the pipe *h*, exhausting the air only from the receptacle containing the cans, jars, &c., until the desired vacuum is obtained. At this moment foot-pressure is applied to the lever *c'*, the rod *c²* is elevated, raising the platform *c* and bringing the covers with force against the under side of the platen *d*, and this foot-pressure is maintained, so as to keep the covers tightly closed, while the vacuum is reduced and until the air is admitted to the receptacle *b* to seal the covers, and this is accomplished by opening the valve *l*, so that the tank will get the benefit of the higher vacuum in the machine, and then closing the valve *i* between the machine and the pump, so that the pump will draw only on the tank. This three-way valve *i* is to be so closed as to open up communication through said valve for the atmosphere to pass by the pipe *h* into the receptacle and effectually seal the covers. After the admission of air to the receptacle, which has the effect of balancing the pressure within the receptacle with that of the atmosphere, the platform *c* is to be lowered, so as to free the covers of the cans, jars, or other packages of contact with the platen *d*. The cover *b'* is now let down, so as to open up the receptacle for the removal of the cans, jars, or other packages the covers of which have been sealed by atmospheric pressure. While the cans, jars, &c., are being removed from the receptacle and others placed therein the covers of which are to be sealed the valve *l* is opened, so that the pump can work to exhaust the air from the vacuum-tank *f*.

The operation or method herein described of sealing the covers of cans, jars, &c., is successively repeated.

I claim as my invention—

1. The combination with a receptacle adapted to receive the cans, jars, &c., the covers of which are to be sealed by atmospheric pressure, of a vacuum-tank, an air-pump, a pipe extending from the air-pump to the receptacle, a branch pipe from the vacuum-tank to said pipe and valves in said pipes by which a partial vacuum is first established in the receptacle and then as complete a vacuum as desired and by which thereafter the pressure in the machine and vacuum-tank may be equalized for the benefit of the tank and air be then admitted to the receptacle so that the same may be opened and the jars, cans, &c., with their sealed covers removed and replaced by others to be sealed.
2. The combination with a receptacle adapted to receive the cans, jars, &c., the covers of which are to be sealed by atmospheric pressure, of a vacuum-tank, an air-pump, a pipe extending from the receptacle

to the air-pump, a three-way valve in the line of said pipe, a pipe from the vacuum-tank to the aforesaid pipe connected therewith between the air-pump and said three-way valve, and a two-way valve in the line of said pipe.

3. A unitary apparatus for sealing the covers of cans, jars or other packages by atmospheric pressure, comprising a receptacle receiving said cans, jars, &c., and adapted to be closed air-tight, devices connected with said receptacle for pressing the covers of said cans, jars, &c., to their seats and holding them temporarily under pressure, an adjacent vacuum-tank, an adjacent air-pump, a pipe from said receptacle to said air-pump by which the air may be exhausted directly from said receptacle, and a three-way valve in the line of said pipe, a pipe from the vacuum-tank to the aforesaid pipe joining therewith between the air-pump and said three-way valve and a two-way valve in the line of said pipe, substantially as set forth.

4. The combination with a receptacle adapted to receive the cans, jars, &c., the covers of which are to be sealed by atmospheric pressure; of a vacuum-tank, an air-pump, communicating passage-ways between the pump and receptacle and the tank, pump, and receptacle, and devices for controlling the said passage-ways, whereby the tank may be caused to exhaust from the receptacle first and the pump thereafter exhaust from the receptacle prior to the sealing of the covers and after the sealing an equilibrium be established between the receptacle and tank prior to admitting the air to the receptacle.

5. The combination with a receptacle adapted to receive the cans, jars, &c., the covers of which are to be sealed by atmospheric pressure, of a vacuum-tank, an air-pump, communicating passage-ways between the pump and receptacle and the tank, pump, and receptacle, devices for controlling the said passage-ways, whereby the tank may be caused to exhaust from the receptacle first, and the pump thereafter exhaust from the receptacle prior to the sealing of the covers and after the sealing an equilibrium be established between the receptacle and tank prior to admitting the air to the receptacle and also whereby the pump may act directly upon the tank to create a vacuum therein.

6. The combination with a receptacle adapted to receive the cans, jars, &c., the covers of which are to be sealed by atmospheric pressure and devices for forcing the covers of said jars, cans, or other packages to their seats and holding them closed and devices connected to the receptacle for admitting the atmosphere to seal the covers prior to opening the same, of a vacuum-tank, an air-pump, communicating passage-ways be-

tween the pump and receptacle and the tank, pump, and receptacle, and devices for controlling the said passage-ways, whereby the tank may be caused to exhaust from the receptacle first and the pump thereafter exhaust from the receptacle prior to the sealing of the covers and after the sealing an equilibrium be established between the recep-

tacle and tank prior to admitting the air to the receptacle.

Signed by me this 8th day of July, 1905.

CHARLES CORNWELL HOVEY.
